US0D1046619S

(12) **United States Design Patent** (10) **Patent No.:** **US D1,046,619 S**
(45) **Date of Patent:** **** Oct. 15, 2024**

(54) **LID**

(71) Applicant: **YETI Coolers, LLC**, Austin, TX (US)

(72) Inventors: **Dustin Bullock**, Austin, TX (US);
Steve Charles Nichols, Austin, TX (US);
Edward Abante, Austin, TX (US);
Evan Goldberg, Austin, TX (US)

(73) Assignee: **YETI Coolers, LLC**, Austin, TX (US)

(**) Term: **15 Years**

(21) Appl. No.: **29/814,428**

(22) Filed: **Nov. 5, 2021**

Related U.S. Application Data

(63) Continuation of application No. 29/751,504, filed on Sep. 22, 2020, now Pat. No. Des. 935,268, which is a continuation of application No. 29/667,017, filed on Oct. 17, 2018, now Pat. No. Des. 897,151.

(57) **CLAIM**

The ornamental design for a lid, as shown and described.

DESCRIPTION

FIG. 1 is a top, front, right perspective view of a lid showing our new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a top, front, right perspective view of a lid showing our new design in its exemplary environment;

FIG. 8 is a top, front, right perspective exploded view of a lid showing our new design;

FIG. 9 is a front view thereof;

FIG. 10 is a rear view thereof;

FIG. 11 is a right side view thereof;

FIG. 12 is a left side view thereof;

FIG. 13 is a top view thereof; and,

FIG. 14 is a top, front, right perspective exploded view of a lid showing our new design in its exemplary assembly.

The broken lines depicting the remainder of the lid show features that form no part of the claimed design.

1 Claim, 14 Drawing Sheets
